US0D1065087S

(12) **United States Design Patent** (10) **Patent No.:** **US D1,065,087 S**
(45) **Date of Patent:** **** Mar. 4, 2025**

(54) **ELECTRICAL RECEPTACLE**

- (71) Applicants: **Randell E. Pate**, Jenison, MI (US);
Ryan J. Alt, Byron Center, MI (US)
- (72) Inventors: **Randell E. Pate**, Jenison, MI (US);
Ryan J. Alt, Byron Center, MI (US)
- (73) Assignee: **Norman R. Byrne**, Ada, MI (US)

(**) Term: **15 Years**

(21) Appl. No.: **29/802,889**

(22) Filed: **Aug. 9, 2021**

Related U.S. Application Data

- (63) Continuation-in-part of application No. 29/660,274, filed on Aug. 20, 2018.

(57) **CLAIM**

The ornamental design for an electrical receptacle, as shown and described.

DESCRIPTION

FIG. 1 is a top perspective view of an electrical receptacle showing our new design;

FIG. 2 is a bottom perspective view thereof;

FIG. 3 is a front end elevation view thereof;

FIG. 4 is rear end elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The broken lines are for the purpose of illustrating portions of the article that form no part of the claimed design.

1 Claim, 5 Drawing Sheets
